UNITED STATES PATENT OFFICE.

ARTHUR BOMBOY, OF CHARLOTTE, NORTH CAROLINA.

INK-RECEPTACLE.

1,364,692.

Specification of Letters Patent.

Patented Jan. 4, 1921.

Application filed May 16, 1919. Serial No. 297,599.

To all whom it may concern:

Be it known that I, ARTHUR BOMBOY, a citizen of the United States, residing at Charlotte, in the county of Mecklenburg and State of North Carolina, have invented new and useful Improvements in Ink-Receptacles, of which the following is a specification.

This invention relates to ink receptacles. 10 The object of the invention is to provide a receptacle especially designed for use in blacking the soles of shoes.

Another object is the provision of a device of this character, having a reservoir 15 and a trough, so arranged to regulate the quantity of fluid in the latter and into which a brush is adapted to be dipped.

Another object is to provide the mouth of 20 the trough with oppositely and inwardly extending flanges, one of which is positioned below the other to provide wiping means for the brush and to assist in filling the reservoir, the said flanges also being of novel formation.

25 Other objects and advantages of the invention will appear as the following description is read in connection with the accompanying drawings.

In the drawings:

30 Figure 1 is a perspective view of the invention.

Fig. 2 is a vertical sectional view of the same.

Referring to the drawings in detail, like 35 characters of reference denote corresponding parts throughout the several views.

The receptacle, as illustrated, comprises a reservoir 10 of preferably rectangular formation, the said reservoir being entirely 40 closed, except for the opening 11 located at the bottom of a wall 12.

A trough 13 is formed on or secured to the reservoir against the wall 12 and the opening 11 provides communication between the 45 interior of the reservoir and the said trough, the latter being open at the top, as indicated at 14. By this means the depth of the fluid within the trough is controlled by the formation of an air seal above the top of

the opening 11, so that only a predetermined quantity of fluid will remain in the trough. 50

The mouth or open end 14 of the trough is provided upon its opposite sides with oppositely and inwardly extending flanges 15 55 and 16, the latter being disposed below the former. These flanges provide wiping edges for each side of the brush, so as the latter is withdrawn, it may be first wiped against the flange 16 and moved over and wiped 60 against the flange 15, thus removing the surplus ink from both sides of the brush in the act of withdrawing the latter from the trough. The flange 15 is formed by an extension of the top wall 17 of the reservoir, 65 the said extension being bent over an extension or flange 18 formed at the top of the wall 12. The flange 16 is formed by an extension of the front wall 19 of the trough, the said extension being bent upon itself in- 70 wardly and having its extremity extending inward and downward to aid in the insertion of the brush within the trough and to provide a more convenient wiping edge for the brush. 75

It is believed that from the foregoing description and accompanying drawings, the construction, use and advantages of the invention will be apparent. The right is reserved to make such changes as properly fall within the scope of the appended claim. 80

Having described the invention, what is claimed is:

An ink receptacle comprising a reservoir formed of a receptacle having an opening 85 in one wall thereof adjacent the bottom, an outwardly and upwardly flaring trough positioned upon the outside of the reservoir, the opening in the latter providing communication between the reservoir and 90 trough, inwardly extending flanges located upon opposite edges of the open end of the trough, one of said flanges being formed by extending the top wall of the reservoir and bending the said extension over an extension 95 of the side wall.

In testimony whereof I affix my signature.

ARTHUR BOMBOY.
